Application April 8, 1944, Serial No. 113,183

Term of patent 14 years

(Cl. D41—1)

To all whom it may concern:

Be it known that I, Henry B. Cohen, a citizen of the United States, residing in the city, county, and State of New York, have invented a new, original, and ornamental Design for a Pulley Block, of which the following is a specification, reference being had to the accompanying drawing, forming a part thereof, in which:

Fig. 1 is a front elevational view of a pulley block showing my new design;

Fig. 2 is a side elevational view thereof taken from the left of Fig. 1; and

Fig. 3 is a side elevational view thereof taken from the right of Fig. 1.

I claim:

The ornamental design for a pulley block, as shown.

HENRY B. COHEN.
